UNITED STATES PATENT OFFICE.

EDWIN M. GRAY, OF EVERETT, WASHINGTON.

AUXILIARY LOG-SUPPORTING MEANS FOR CLAPBOARD-SAWING MACHINES.

1,381,183.

Specification of Letters Patent. Patented June 14, 1921.

Application filed September 20, 1920. Serial No. 411,460.

To all whom it may concern:

Be it known that I, EDWIN M. GRAY, a citizen of the United States of America, and resident of the city of Everett, in the county 5 of Snohomish and State of Washington, have invented certain new and useful Improvements in Auxiliary Log-Supporting Means for Clapboard-Sawing Machines, of which the following is a specification.

10 My invention relates to clapboard sawing machines and comprises particularly an auxiliary log-supporting means therefor.

An object of my invention is to provide means whereby logs of larger diameter than 15 the maximum for which the machine is designed may be properly and conveniently sawed into clapboards.

Another object of my invention is to provide means whereby logs having rotten or 20 hollow cores, whether of the usual small diameter or larger than the usual size, may be sawed in such manner as to utilize the good material.

Another object of my invention is to provide means whereby logs of large diameter 25 may be most efficiently sawed, producing thereby the greatest number of clapboards which it is possible to saw from a given log.

My invention comprises those novel parts 30 and combinations thereof which are shown in the accompanying drawings, described in the specification, and particularly defined by the claims terminating the same.

In the accompanying drawings I have 35 shown my invention in the form which is now preferred by me, although I do not intend to limit myself to the exact construction shown.

Figure 1 is a plan view of a clapboard 40 sawing machine illustrating my invention in use in connection therewith.

Fig. 2 is a transverse section through a clapboard sawing machine illustrating my invention in use.

45 Fig. 3 is a perspective illustrating my improved constructions separate from the machine.

In sawing clapboards from logs with existing apparatus, it is the practice to center 50 the log upon the centers of the machine, to dress its surface, and then to make a series of longitudinally extending radial cuts in the log, and then breaking out the boards so formed. It often occurs that a log has 55 an unsound core. The centers of the machine will not hold in this core. Often the

logs or bolts which it is desired to cut into clapboards are too large to be handled by the machines installed. Furthermore, it would make such machines unwieldy and 60 difficult to handle if they were made large enough to handle these logs as they are sawed into proper lengths. Such logs may be split up into bolts which are then of a proper size to fit into the machine but which 65 cannot be accommodated by the centers of the machine without considerable waste. My device is intended to engage the ends of such bolts so that they may be sawed in the machine with the least possible waste. Fur- 70 ther, if the portion of the heart of the log which forms a part of the split bolt is unsound, this portion of the bolt need not be sawed and my device is so designed that it will firmly grip the sound portion of the 75 log, and will not need to grip the unsound portion.

My device has another advantage. It often occurs that where a log is larger than the ordinary, the cuts will be more widely 80 spaced at the periphery of the log than is desirable or necessary, and a considerable amount of wastage occurs, as the clapboards must be of uniform width at their lower edges. By the use of my device it is possi- 85 ble to regulate the sawing of the bolts so that the widest part of the clapboards, as sawed, is not greater than the proper width. Clapboards may be sawed from the outer portion of a log or bolt, and after the series 90 sawed has been removed the center of rotation may be changed and a second series sawed from the same log. In this manner I find that I increase the number of clapboards sawed from a single large log, from 95 five to ten per cent.

The clapboard sawing machine may be of any suitable type. That which I have shown in connection with my invention consists of a live center 1 and a dead center 10 sup- 100 ported in a suitable frame 11 which is mounted to slide vertically by means of the rack 12 and pinion 13. The frame 14, upon which the frame 11 slides, is longitudinally movable upon the base 15 by means of a 105 rack 16 and pinion 17. A circular saw 2 is supported upon the base 15 and is rotated by suitable power means, as through the pulley 20. The above details, save the centers, may be altered as desired, as they form no 110 part of my invention.

I provide a dog 3 which is shown herein

as a plate and which has in its central portion one or more center-receiving holes or sockets 31. These are adapted to be received upon the live center 1 or the dead center 10. At one end of the dog 3 I provide a series of bolt-engaging members which I have shown as the inwardly facing teeth 32. These are preferably arranged transversely of the dog 3 or upon a circular arc. At the end opposite the teeth 32 I provide a socket or hole for the reception of a spacer bar to be later described. I have shown this hole as formed by means of a loop 33 secured upon the end of the dog 3.

15 The spacer bar 4 is of a length approximating the distance between the centers 1 and 10 of the machine. At one or at both ends it may be provided with a series of transverse pin-receiving holes 41. A pin 42 is adapted to be received in the holes 41 and to abut against the inner face of the dog 3 or its loop 33 which receives the end of the bar 4. The purpose of these holes 41 is to provide means for varying the effective length of the bar 4. A counter-balance 45 upon the bar 4 may be employed if desired.

In use the teeth 32 are pressed or driven into the end of a log or bolt which is to be cut into clapboards. The teeth must be spaced inward from the periphery of the log, which is indicated at L, sufficiently to avoid the saw 2 but the teeth should engage the log inward from its core enough to avoid rotten portions. The dog may be pivoted upon one or several different centers, depending upon which of the holes 31 is placed upon the centers of the machine. The log L and the spacer bar 4 space the dogs 3 apart and their central portions are urged inward by the opposing centers 1 and 10. In this manner the log is securely gripped by the dogs 3 and the log may be turned while so gripped by the dogs.

It is evident that by the use of my device, 45 unsound cores may be avoided by the centers, whether they be cores of small logs or split bolts. It is also evident that by employing the different center-receiving holes 31 in succession, the angle of the 50 cut with respect to the center of the log may be changed and thus clapboards may be sawed first from the outer portion of the log and then cut again from its central portion. Where sawing a log inclining 55 to the oval in cross-section, by changing the centers from one to another of the holes 31, the radius of swing of the log is changed, and the clapboards may be kept more uniform as to depth of cut and width at their 60 base.

What I claim as my invention is:

1. An auxiliary dog for use with clapboard sawing machines comprising a member having centering means therein, a set

of bolt-engaging members at one end thereof, 65 and having means at its opposite end for the engagement of a spacing bar.

2. An auxiliary dog for use with clapboard sawing machines comprising a plate having centering means in its central portion, a set of bolt-engaging teeth at one end thereof, and having a socket at its opposite end for the reception of a spacing bar. 70

3. An auxiliary dog for use with clapboard sawing machines comprising a plate 75 having a hole in its central portion for the reception of a center of the machine, a set of bolt-engaging teeth arranged upon a circular arc at one end of the plate, and said plate having a socket at its opposite end for the 80 reception of a spacing bar.

4. In a clapboard sawing machine, an auxiliary bolt-gripping means comprising a pair of dogs adapted to be engaged by the opposite machine centers, bolt-engaging 85 means at one end of each of said dogs, and a spacing bar interposed between the ends of said dogs which are opposite the bolt-engaging means.

5. In a clapboard sawing machine, an auxiliary bolt-gripping means comprising a pair of dogs having means in their central portion adapted to be engaged by the opposed centers of the machine, inwardly-facing, bolt-engaging teeth at one end of each 95 of said dogs, and a spacing bar interposed between the ends of said dogs which are opposite said teeth.

6. In a clapboard sawing machine, an auxiliary bolt-gripping means comprising 100 a pair of dogs adapted to be engaged by the opposite machine centers, bolt-engaging means at one end of each of said dogs, a spacing bar interposed between the ends of said dogs which are opposite the bolt-engaging 105 means, and means for adjusting the effective length of said spacing bar.

7. In a clapboard sawing machine, an auxiliary bolt-gripping means comprising 110 a pair of dogs having means in their central portion adapted to be engaged by the opposed centers of the machine, bolt-engaging means at one end of each of said dogs, a spacing bar interposed between the ends of said dogs which are opposite the bolt 115 engaging means, one of said dogs having bar-receiving holes in this end, and said bar having a longitudinally-spaced series of transverse holes near an end and a pin adapted to be received in any one 120 of said transverse holes and to abut against the inner face of said dog, the opposite end of said bar being held against the inner face of the dog at this end.

Signed at Everett, Snohomish county, 125 Washington, this 31st day of August, 1920.

EDWIN M. GRAY.
